CLAIM

The ornamental design for a smartphone, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, right, rear orthogonal view of a first embodiment of a smartphone showing the new design; FIG. 2 is a bottom, right, rear orthogonal view of the invention illustrated in FIG. 1;

FIG. 3 is a front view of the invention illustrated in FIG. 1;

FIG. 4 is a rear view of the invention illustrated in FIG. 1;

FIG. 5 is a right side view of the invention illustrated in FIG. 1;

FIG. 6 is a left side view of the invention illustrated in FIG. 1;

FIG. 7 is a top view of the invention illustrated in FIG. 1; FIG. 8 is a bottom view of the invention illustrated in FIG. 1;

FIG. 9 is an enlarged front view of the portion indicated by the dot-dashed broken-lined circle of FIG. 3 labeled 9; FIG. 10 is a top, right, rear orthogonal view of a second embodiment of a smartphone showing the new design; FIG. 11 is a bottom, right, rear orthogonal view of the invention illustrated in FIG. 10;

FIG. 12 is a front view of the invention illustrated in FIG. 10; FIG. 13 is a rear view of the invention illustrated in FIG. 10; FIG. 14 is a right side view of the invention illustrated in FIG. 10;

FIG. 15 is a left side view of the invention illustrated in FIG. 10;

FIG. 16 is a top view of the invention illustrated in FIG. 10; FIG. 17 is a bottom view of the invention illustrated in FIG. 10;

FIG. 18 is an enlarged front view of the portion indicated by the dot-dashed broken-lined circle of FIG. 12 labeled 18; FIG. 19 is a top, right, rear orthogonal view of a third embodiment of a smartphone showing the new design; FIG. 20 is a bottom, right, rear orthogonal view of the invention illustrated in FIG. 19;

FIG. 21 is a front view of the invention illustrated in FIG. 19; FIG. 22 is a rear view of the invention illustrated in FIG. 19; FIG. 23 is a right side view of the invention illustrated in FIG. 19;

FIG. 24 is a left side view of the invention illustrated in FIG. 19;

FIG. 25 is a top view of the invention illustrated in FIG. 19; FIG. 26 is a bottom view of the invention illustrated in FIG. 19;

FIG. 27 is an enlarged front view of the portion indicated by the dot-dashed broken-lined circle of FIG. 21 labeled 27; FIG. 28 is a top, right, rear orthogonal view of a fourth embodiment of a smartphone showing the new design; FIG. 29 is a bottom, right, rear orthogonal view of the invention illustrated in FIG. 28;

FIG. 30 is a front view of the invention illustrated in FIG. 28; FIG. 31 is a rear view of the invention illustrated in FIG. 28; FIG. 32 is a right side view of the invention illustrated in FIG. 28;

FIG. 33 is a left side view of the invention illustrated in FIG. 28;

FIG. 34 is a top view of the invention illustrated in FIG. 28; FIG. 35 is a bottom view of the invention illustrated in FIG. 28; and,

FIG. 36 is an enlarged front view of the portion indicated by the dot-dashed broken-lined circle of FIG. 30 labeled 36. The broken lines in the drawings depict portions of the smartphone that form no part of the claimed design. The parallel diagonal shading lines on the rear of the smartphone in the embodiments of FIGS. 1-8 and FIGS. 1-9 indicate transparency. The dot-dashed broken-lined circles of FIGS. 3, 12, 21, and 30 form no part of the claimed design.
